UNITED STATES PATENT OFFICE.

WILLIAM W. ROBERTSON AND EVERETT E. CLARK, OF WORCESTER, MASSACHUSETTS,
ASSIGNORS TO CROMPTON & KNOWLES LOOM WORKS, OF WORCESTER, MASSACHUSETTS, A CORPORATION OF MASSACHUSETTS.

PILE-FABRIC LOOM.

Application filed January 5, 1923. Serial No. 610,748.

This invention relates to a pile fabric loom and particularly to an improved device for supporting an operatively positioned yarn tube frame therein.

5 There is at the present time a heavy demand for pile fabric looms of greater width than have been heretofore commonly used, the particular object being to produce a wide rug or carpet without piecing together 10 several separate widths of carpet to produce the desired width. These wide looms require long and relatively heavy tube frames which should be supported at one or more intermediate points to properly position the 15 tuft yarns and to cause the same amount of yarn to be delivered from each yarn tube.

It is the object of our invention to provide an improved device for thus additionally supporting the tube frames and particularly to provide an improved and simplified actuating mechanism therefor.

Our invention further relates to arrangements and combinations of parts which will be hereinafter described and more particularly pointed out in the appended claims.

A preferred form of our invention is shown in the drawings in which

Fig. 1 is a sectional side elevation of parts of a loom embodying our improvements;

30 Figs. 2 and 3 are similar views showing certain parts in different successive positions; and

Fig. 4 is a plan view of certain actuating connections.

35 Referring to the drawings, we have shown a portion of the loom frame 10 of a pile fabric loom having the usual cam shaft 11 rotatably mounted in bearings theron. We have also indicated a lay 12 supporting a 40 reed 13, a rear knife 14, and a tube frame 16 having a plurality of yarn tubes 17 secured thereto and supporting the yarn spools 18. The parts thus far described are of the usual type and in themselves form no part of our present invention which relates particularly to the means for additionally supporting the frame 16 at an intermediate point.

45 For this purpose we provide a frame engaging device comprising a support 19 forming the end of a lever 20 which in turn is supported at one end by a bell crank 21 and at an intermediate point by a link 22. The bell crank 21 is pivoted on a stud 23 fixed

in a bracket 24 (Fig. 4) secured to a cross beam 10^a of the loom frame 10.

The upper end of the link 22 is adjustably connected to a lifting arm 25 which swings about the stud 23. An actuating member 26 is also pivoted on the stud 23 and has a yielding connection with the bell crank 21, this connection comprising a rod 27 mounted in one arm of the bell crank 21 and extending loosely through a recessed projection 28 on the member 26. A spring 29 and lock nuts 30 are placed on the lower end of the rod 27, the spring receiving the downward thrust of the member 26 which thus yieldingly actuates the bell crank 21.

The member 26 has an extension 26^a beyond its pivot which is slotted to receive an adjustable roll 30^a positioned to engage the under side of the lifting arm 25. The actuating member 26 is adjustably connected by a link 31 to a lever 32 mounted on a fixed pivot 33 and having a roll 34 engaged by a cam 35 mounted on the cam shaft 11. The cam 35 is preferably formed with two steps on its advancing face, for a purpose to be described. A spring 36 retains the roll 34 in contact with the cam and yieldingly withdraws the tube engaging support 19 from operative position.

Having thus described the details of construction of our invention, the use and operation thereof is as follows:

Assuming that the parts are in the position shown in Fig. 1, with the tube frame 16 disposed in operative position, the first or inner step of the cam 35 will actuate the member 26 through the lever 32 and link 31, drawing the member 36 downward and thus applying yielding pressure through the spring 28 to the bell crank 21. Such movement of the bell crank advances the support 19 toward the tube frame, and the member is also given a slight downward movement by reason of the relation of the pivots of the link 22.

The parts are thus moved to the position shown in Fig. 2 in which the support 19 projects under and engages the tube frame 16. The roll 30 on the extension 26^a has been moving upward at the same time but on account of lost motion between the parts it does not engage the lifting arm 25 until the support 19 has reached the position shown in Fig. 2.

- The second and outer step of the cam 35 then engages the roll 34 on the lever 32, moving it further in the same direction and causing the roll 30 on the actuating member 26 to lift the arm 25 as indicated in Fig. 3, raising the support 19 and tube frame 16 at an intermediate point as the ends of the tube frame are raised to draw the tuft yarns from the spools.
- 5 10 We thus secure two different operative movements for the support 19 by using a single cam 35 and a single cam lever 32. After the lever 32 is released by the cam 35, the spring 36 returns the parts to their normal inoperative position. We have found that the support 19 may be desirably formed of wire rod or other slightly flexible material as an entirely rigid structure is not required.
- 15 20 Our improved construction is thus exceedingly simple and reliable, as well as inexpensive to manufacture and easily mounted and adjusted on the loom. It will be understood that more than one support 19 may be 25 provided where the width of the loom makes it desirable.
- Having thus described our invention and the advantages thereof, we do not wish to be limited to the details herein disclosed 30 otherwise than as set forth in the claims, but what we claim is:—
- 35 1. In a pile fabric loom having a plurality of tube frames movable successively to operative position, in combination, a support effective to engage an operatively positioned tube frame at a point intermediate the ends of the frame, and means to move said support, said means comprising a continuously moving cam, a single cam lever 40 actuated thereby, and yielding and positive connections from said cam lever to said support through which the frame-engaging end of said support is given successive substantially horizontal and vertical operative 45 movements, said cam lever being effective
- through said yielding and positive connections to yieldingly actuate said support during its first and horizontal movement and to positively actuate said support during its second and vertical movement. 50
2. In a pile fabric loom having a plurality of tube frames movable successively to operative position, in combination, a support effective to engage an operatively positioned tube frame at a point intermediate 55 the ends of the frame, and means to move said support, said means including a two-step cam, a cam lever engaged thereby, and connections from said cam lever to said support through which engagement of said cam lever by the first and inner step of said cam produces a substantially horizontal positioning movement of the frame-engaging end of said support and engagement of said cam lever by the second and outer step of 60 said cam produces a substantially vertical operative movement of the frame engaging end of said support.
3. In a pile fabric loom having a plurality of tube frames movable successively to 65 operative position, in combination, a device effective to engage an operatively positioned tube frame at a point intermediate the ends of the frame, and means to move said device, said means comprising a lifting arm, 70 a link connecting said arm to an intermediate point in said device, a bell crank connected to one end of said device and a cam-actuated member movable in a single direction to first yieldingly engage said bell 75 crank and to thereafter positively engage said arm through a lost motion connection, thereby giving the frame engaging end of said device successive substantially horizontal and vertical movements. 80
- In testimony whereof we have hereunto affixed our signatures.
